Primary Examiner — Dominic Simone(74) *Attorney, Agent, or Firm* — Marshall A. Lerner; Marvin H. Kleinberg; Kleinberg & Lerner, LLP**CLAIM**

The ornamental design for a shoe upper, as shown and described.

DESCRIPTION

FIG. 1 is a front left side perspective view of a shoe upper in accordance with my new design.

FIG. 2 is a rear right side perspective view thereof;

FIG. 3 is a left side view thereof; and,

FIG. 4 is a right side view thereof.

Broken lines showing the remainder of the shoe in the figures are for illustrative purposes only and form no part of the claimed invention.
